UNITED STATES PATENT OFFICE.

JOSEPH AUGUSTUS ANGLADA, OF NEW YORK, N. Y., ASSIGNOR TO THE ANGLADA COMPANY, A CORPORATION OF MICHIGAN.

DEMOOUNTABLE RIM.

1,087,628.

Specification of Letters Patent. Patented Feb. 17, 1914.

Application filed December 13, 1911. Serial No. 665,414.

To all whom it may concern:

Be it known that I, JOSEPH A. ANGLADA, a citizen of the United States, and a resident of New York city, borough of Brooklyn, in the county of Kings and State of New York, have invented certain new and useful Improvements in Demountable Rims, of which the following is a specification.

My invention relates to rims for wheels and the object of my invention is to provide a demountable rim of simple and durable construction.

Referring to the drawings which form a part of this specification Figure 1 is a side view of a wheel having mounted thereon a rim embodying my invention. Fig. 2 is a view of a section of the felly of a wheel with a band thereon which carries parts of the interlocking means for securing the rim to the band. Fig. 3 is a view of a section of the rim carrying coacting means for locking the rim to the band. Fig. 4 is a perspective view of one of the holding clips carried by the band. Fig. 5 is a perspective view of one of the locking lugs carried by the rim.

Fig. 6 is an inverted view of the locking element shown in Fig. 5 which is carried by the rim and co-acts with the holding clips to secure the rim to the band. Fig. 7 is a side view of the element disclosed in Fig. 6. Fig. 8 is a development of a fragment of the band showing the means used for throwing the co-acting parts of the holding elements together. Fig. 9 is a cross sectional view on line A—A of Fig. 8 illustrating the view on line A—A of Fig. 8 of the rim locked to the band. Fig. 10 is a cross sectional view on line B—B of Fig. 8. Fig. 11 is a plan view of the portion of the rim where the valve of the pneumatic tube passes through. Fig. 12 is a cross sectional view of the rim, band, and felly the section through the band and felly being taken on line C—C of Fig. 11, the section through the rim being taken across the opening for the valve of the pneumatic tire.

20, indicates a portion of the felly of a wheel on which is mounted a plain band 21. Mounted on the band, preferably at equal distances apart circumferentially, are clips 22 which are nearly as wide as the band, and each is provided with a cylindrical shaped depression 23, as illustrated. The axis of the depression 23 extends at an angle of

preferably seven degrees relative to the base of the element 22, although any other convenient angle may be adopted if desired.

Fastened to the inner side of the rim 25 are holding elements or lugs constituting abutments 26 formed with inclined cylindrical end faces 27 adapted to engage with the depressions 23 of the clips 22. When the rim is mounted upon the band and one is rotated relative to the other, the two are wedged tightly to each other through the engagement of these clips and abutments.

For rotating the rim with reference to the band, the following device is provided: Carried by the band 21 and felly 20 is an eccentric 28, the shaft 29 of which extends through the band and felly and the end 30 of which is preferably formed rectangular as illustrated. A rectangular plate 31 provided with a circular opening 32 is mounted upon the eccentric the sides of which are inclined as illustrated, and the periphery of the eccentric and the interior wall of the plate engaging the same are both beveled or tapered so as to firmly lock when the eccentric is drawn inward. By turning the shaft 29 the eccentric is rotated advancing the plate 31 and through plates 33 and 34 fixed to the rim and engaged by the plate 31, the rim is rotated to wedge the same against the band, or to release the same depending upon the direction of rotation of the eccentric. The thickness of the eccentric is made somewhat less than the thickness of the eccentric plate so that in case the eccentric should stick in the plate due to rust or other causes, the eccentric may be loosened therefrom by striking the lower end of the shaft 29, and thus disengaging the eccentric from the plate. This eccentric may be clamped to the eccentric plate and firmly fixed by turning the nut 32 threaded upon the eccentric shaft and jamming the same against the felly.

To permit the valve tube 38 of the tire to be readily inserted through the felly, the latter is provided with a flaring aperture 35 of the shape indicated by dotted lines 36 and the rim is provided with a circular aperture 37. The shape of the aperture 35 is such as to permit of the tube 38 of the tire being easily passed through it and to allow also a certain amount of movement circum-

ferentially of the felly when the rim is rotated relative to the felly in securing the rim to the band.

In placing the rim on the band after the tire 39 has been secured to the rim, the tube 38 is first guided into the hole 35 of the felly and this brings the plates 33 and 34 in position at each side of the plate 31 when the plate is in the relative position to the rim as shown in Fig. 8. The rim is then shoved over the band to the position indicated in Fig. 8, and moved circumferentially by rotating the eccentric to force the abutments 26 into engagement with the holding clips 22, after which the nut 30 is screwed up to lock the parts firmly together.

By using a plain band and simple fastening means, the cost of construction is materially reduced; moreover, the rim may be removed from either side of the band. Any type of rim for pneumatic or solid tires may be used as well as the clincher type rim for pneumatic tires herein illustrated. The invention is also applicable to wire as well as wooden wheels.

It will be noted that the holding clip 22 is provided with an extension 22^a forming an abutment. This extension is for the purpose of permitting the lugs carried by the rim to abut against it, thus insuring the accurate mounting of the rim over the band before the eccentric is operated and serves to guide the abutments into the depressions in the holding clips as will be readily understood.

Having thus described my invention, I claim:

1. A demountable rim comprising a circular band, holding clips mounted on said band spaced apart circumferentially, a rim having lugs connected to the inner periphery thereof and spaced apart from each other circumferentially corresponding to the distance which the clips are separated on said band, and means for forcing said lugs into locking engagement with said clips, said means comprising an eccentric, a movable block mounted thereon, and a projection on the rim engaging said block.

2. A demountable rim comprising a circular band, holding clips mounted on said band spaced apart circumferentially, a rim having lugs connected to the inner periphery

thereof and spaced apart from each other circumferentially corresponding to the distance which the clips are separated on said band, means for forcing said lugs into locking engagement with said clips, said means comprising an eccentric having a beveled periphery, a movable block having a beveled recess mounted on said eccentric, and means for holding said eccentric and block in locked engagement through their beveled contacting surfaces.

3. A demountable rim comprising a circular band, clips mounted on said band spaced apart circumferentially, a rim having lugs connected to the inner periphery thereof and spaced apart from each other circumferentially corresponding to the distance which the clips are separated on said band, means comprising an eccentric the shaft of which projects through said band, an eccentric plate held in position by said eccentric, a projection on the rim engaged by said plate, and means for locking said eccentric in fixed position to said plate.

4. A demountable rim comprising a circular band, clips mounted on said band spaced apart circumferentially, a rim having lugs connected to the inner periphery thereof and spaced apart from each other circumferentially corresponding to the distance which the clips are separated on said band, means comprising an eccentric the shaft of which projects through said band and is adapted to project through the felly of the wheel on which said band is mounted, an eccentric plate held in position by said eccentric and of greater thickness than same, and means for locking said eccentric in fixed position to said plate.

5. In a wheel, a felly, a rim adapted to be locked to said felly, and locking means comprising an eccentric having a tapered periphery, a block having a tapered seat for the eccentric, and means for wedging said tapered surfaces together to lock the eccentric in adjusted position.

Signed at New York city in the county of New York and State of New York this 9th day of September A. D. 1911.

JOSEPH AUGUSTUS ANGLADA.
